Samuel F. Pratt of Boston, Mass.
Assignor to
Fagger, Treadwell & Perry of Albany, N. Y.
Letters Patent No 488 Dated Aug 17th 1852.

The schedule referred to in these Letters Patent and making part of the same

To whom it may concern:

Be it known that I, Samuel F. Pratt of the City of Boston, State of Massachusetts have produced a new ornamental design for the plates of a Six Plate Stove, and I do hereby declare that the annexed drawings are full & accurate delineations of the ornamented parts with their several ornaments the side plate which is not represented being similar to the one represented and where portions of plates only are shown, the portions not shown be-
